FIG. 4.

UNITED STATES PATENT OFFICE.

GUSTAV REHE, OF CHICAGO, ILLINOIS.

LATCH.

1,286,774.

Specification of Letters Patent.

Patented Dec. 3, 1918.

Application filed November 22, 1917. Serial No. 203,373.

To all whom it may concern:

Be it known that I, GUSTAV REHE, a citizen of the United States, residing at Chicago, county of Cook, and State of Illinois, have invented certain new and useful Improvements in Latches, of which the following is a specification.

This invention relates to improvements in latches, particularly automatic night latches.

An object of this invention is to provide a latching device that will permit a door being partially opened and at the same time make it impossible for the said door to be opened wide from the outside.

Another object of the invention is to provide a latch of such a nature that it can be set to automatically spring into latching coöperation with the door as the door closes.

Another object of the invention is to provide a latch that can be set to lock and hold the door in a closed-tight position.

Another object of the invention is to provide a latch with a means for holding the hasp out of service and preventing the latch from functioning.

With these and other objects in view, an embodiment of the invention is illustrated in the accompanying drawings and described in the following specification, the novel features of the invention being more particularly pointed out in the appended claims.

Figure 1 is a front view of a latch shown as it would appear with its proper elements mounted on the door casing and closed door.

Fig. 2 is a top view of the latch shown in Fig. 1.

Fig. 3 is a sectional view, showing the door elements of the latch in section and a fragment of the hasp in full, also a fragmental section of the door and casing.

Fig. 4 is a bottom plan view of the door casing element shown with the cover plate removed.

Referring to the drawings, particularly Fig. 1, the casing 5 is formed by two vertical side walls 6 and a rear end wall 7 connected by a top wall 8. The front and bottom of said casing are open and a slot 9 is cut along the bottom edge of both side walls 6 continuing up to the rear end wall 7, to provide shoulder 10, on which to rest a closing plate. End wall 7 is swelled to form a boss 12 which is provided with a vertical bore 13 terminating in an enlarged counter-bore 14.

Laterally disposed ears 15 are formed by bending a portion of the side walls 6 outwardly at right angles thereto and apertures 16 are provided in said ears to receive fastening members, such as screws or nails to secure the casing in place on a door casing or wherever it is desired to utilize the invention.

A thumb screw has a neck 17 formed on the upper portion of its stem 18 by providing a flat annular flange 19 integral with and near the upper end of said stem. The lower surface of said flange has small lugs 20 so disposed as to register with slots 21 located about 90° apart on the top surface of the top wall 8 of casing 5. The stem of the thumb screw extends downwardly through the bore 13 and projects slightly into the counter-bore 14. A compression spring 22 of slightly smaller diameter than the counter-bore is inserted in said counter-bore and a washer 23 also of slightly smaller diameter than the said counter-bore is secured to the bottom of the stem 18 by means of a screw 24.

The degree of compression on the spring can be regulated by the adjustment of the screw 24.

A flat rectangular plate has the front end cut out for a part of its width in such a manner as to leave projections 26 adjacent its side edges. The rear end of said plate is cut out in a semi-circular shape, and this cut out portion terminates in a narrow slot 27 extending forwardly on the longitudinal center line of the rectangular plate, to provide an opening for a compression coil spring 28, which is inserted over a pin 29, extending forwardly in alinement with said slot, from the side wall of the boss 12. On the longitudinal center line in alinement with the slot 27 just described, a little toward the front end of plate 25 another rectangular slot 30 is cut and it enlarges into a circular shaped slot as it approaches the front end of the plate 25, and is so located that a boss 31 extending downwardly from the top wall of the casing will project into said circular part of the slot 27.

A yielding member 32 formed of a flat piece of metal has ears 33 projecting from its end edge so spaced as to fit between the projections 26 of plate 25. A pintle 34 extends through apertures which have been provided in projections 26 and ears 35. A torsion spring 36 is coiled about pintle 34.

and extends between the ears 33; the free ends of said spring are secured to one of the ears 33 and the plate 25 respectively, in order that the spring may function as a torsion member and keep the yielding member 32 against a closing plate 37.

The closing plate 37 is made of a flat piece of metal of a thickness equivalent to the depth of the slots 9, that are cut along the bottom edge of the side walls 6. Said slots or shoulders are so located in the side walls 6 of the casing that they permit of an easy sliding movement of the rectangular plate 25. The rear end of closing plate 37 is cut out in a semi-circular shape to fit around the boss 12 and an aperture 38 counter-sunk on one side is provided in said closing plate, through which a counter-sunk screw 39 is inserted and has threaded engagement with a tapped hole in the bottom of the boss 31. The closing plate projects beyond the front edge of the casing to provide a stop to resist the tendency of the torsional spring 36 to cause the yielding member 32 to rotate about pintle 34.

Extending upwardly from the front end of the top wall and flush with the side walls 6 of casing 5, are ears 40 having apertures therein to receive a pivot pin 41, which extends therethrough and forms a pivotal relation with the hasp. The yoke of the hasp is apertured and in pivotal relationship with the ears 40 and has a nose 42 extending upwardly from a neck 43 which joins the yoke 35 with the slotted part of the hasp. The closing end 44 of the slotted part of the hasp projects laterally beyond both of its sides and forms stops 45. A torsional spring 46 is coiled about pivot pin 41 and secured at one end to the hasp and the other end extends out parallel with the top of the casing 5 and provides the means that forces the hasp outwardly into coöperation with the other elements of the invention.

A housing or hasp holding bracket 47 (Figs. 1 and 2) is provided, having two bent fingers 48 on its forward end of just sufficient distance apart to permit the neck 43 of the hasp to pass between. The side walls 50 of the housing terminate in cam like projections 49; the outer edges of said projections are so curved as to have sliding engagement with the curvature of yielding member 32. A portion of the lower side walls and rear wall of the housing is bent outwardly at right angles thereto to provide wings 50 and 51; said wings are apertured to receive screws or the like to serve as a means of securing said housing in position.

A boss 52 on the inner side of the upper wall of said housing is provided with a bore, a thumb-screw, spring, washer and fastening means similar or identically the same as that provided in the casing 5.

To put my device into practical use it is

first necessary to secure the casing 5 to the edge of a door casing by any suitable means; the housing 47 to the face of the door in such a position that the neck 43 of the hasp fits between the bent fingers 48 and permits of its passing therebetween without interfering with the said fingers. In the position just described as the door is opened the bent fingers 48 slide over the sides of the hasp and the door is permitted to open until stops 45 strike the fingers and prevent the door from being further opened.

If it is desired to put the latch out of operation so that the door may be opened wide without interference the hasp must be rotated outwardly about its fulcrum for about 180° until the nose 42 passes through a slot 53 in the upper wall of casing 5 and until said nose wedges itself far enough into another slot 30 in the sliding plate 25 to permit a lip 54 in said sliding plate to be forced by the recoil of the spring 28, into locking engagement with said nose. The neck of the hasp being of smaller diameter than the distance between the two bent fingers 48, it can be rotated out of engagement without interference, and the nose being integral with the neck of the hasp they will rotate simultaneously.

With the hasp in the position just described the door is free to open, but in opening cam projections 49 extending from the front ends of housing just below the bent fingers will come into sliding engagement with the edge of the yielding member 32.

When the door is closed the curvature of the projections 49 come into sliding engagement with the yielding member 32 forcing it backwardly against the pressure of the spring 36. This disengages the hook with 105 the lip 54 and the spring 46 secured around the pivotal member throws the hasp back against the housing and the neck 43 passes between the bent fingers 48 thus placed in a position to automatically bring the device 110 into operation again as soon as the door is opened.

If it is desired to put the automatic features of this device out of operation it is only necessary to rotate the hasp backwardly until the nose passes through the slot and engages with the lip 54 in the same manner as just previously described, then pull the thumb screw of the casing 5 upwardly far enough to disengage the lugs 20 120 from the slots 21 and revolve it 90°; the head of said thumb screw will then be in position to prevent the hasp from returning to operative position as the nose becomes disengaged with the lip 54 as the 125 door is opened.

If it is desired to use this device as a means for locking the door and keeping the door tightly closed the thumb screw provided in the upper wall of the housing must 130

be turned 90° and it then engages the hasp and permanently locks the door.

I claim:

1. In a device of the character described, the combination of a hasp support, a hasp pivotally mounted thereon, a hasp holding bracket on the door, and an element for automatically locking the hasp in inoperative position when said hasp has been moved manually to said inoperative position, said hasp holding bracket being adapted to release said locking element automatically when the door is being closed.
2. In a door fastening device, the combination of a hasp support, a hasp pivotally mounted thereon, means for automatically locking said hasp in inoperative position, a hasp holding bracket fastened to the door, and a movable member on said locking means adapted to move relatively to the locking means when said hasp holding bracket is moved in a predetermined direction and adapted to cause displacement of said locking means into release position when said hasp holding bracket is moved in the opposite direction.
3. In a door fastener, the combination of a hasp support, a hasp, a locking plate for automatically holding said hasp in inoperative position, a hasp holding bracket, a member controlled by said hasp holding bracket and pivotally connected with said locking plate, and means for preventing movement of said member about its pivot in one direction.
4. In a door fastener, the combination of a hasp support, a hasp, a plate for automatically locking said hasp in inoperative position, a hasp holding bracket, a member controlled by said hasp holding bracket and pivotally connected with said locking plate, means for preventing movement of said member about its pivot in one direction, said member being movable in the opposite direction upon engagement with said hasp holding bracket, and means for returning said pivotal member to the original position relatively to said locking plate.
5. In a door fastener, the combination of a hasp support, a hasp pivotally mounted thereon, a locking plate slidably carried by said support, a spring acting against said locking plate at one end thereof, a yielding member pivotally mounted to said locking plate at the other end, a hasp holding bracket, and means on the said bracket for swinging said yielding member about its pivotal support when the said bracket is moved in

one direction and for shifting said yielding member and locking plate jointly when said bracket is moved in the opposite direction.

6. In a door fastener, the combination of a hasp support, a hasp pivotally mounted thereon, said hasp being provided with a reduced neck portion and a slotted body of a larger width than the neck portion, a transverse terminal projection extending laterally from the end of said slotted body, and a hasp holding bracket mounted on the door having spaced projecting fingers which when the hasp is in operative position and the door is closed are in opposition to the reduced portion of the hasp and which upon opening movement of said door enter into engagement with the laterally extending portion of the transverse terminal projection of the hasp.

7. In a door fastener, the combination of a hasp support, a hasp pivotally mounted thereon, a locking plate slidably carried by said support, a hasp holding bracket mounted on the door and having fingers which are located at opposite longitudinal edges of said hasp when the door is in closed position, and projecting horn portions on said holding bracket for engaging the locking plate on the hasp support when the door is open.

8. In a door fastener, the combination of a hasp support, a hasp pivotally mounted thereon, means for automatically locking the hasp in inoperative position and for releasing said hasp from inoperative position upon movement of the door with respect to the hasp, means for locking said hasp in operative position, and means independent of said automatically locking means for holding said hasp locked in inoperative position.

9. In a door fastening device, the combination of a hasp support, a hasp pivotally mounted thereon, means carried by said hasp support for automatically locking the hasp in inoperative position when the hasp has been manually moved to said position, means for automatically releasing said automatic locking means upon closure of the door, and means for automatically throwing the hasp to operative position upon the automatic release of said first-named locking means.

In testimony whereof I affix my signature in the presence of two witnesses.

GUSTAV REHE.
